CLAIM

The ornamental design for a tapered brush handle, as shown and described.

DESCRIPTION

FIG. 1 is a perspective view of a brush with a first tapered handle;

FIG. 2 is a side elevation view of the brush of FIG. 1, where the brush handle is symmetrical about a longitudinal axis thereof such that a left side elevation view, a right side elevation view of the brush of FIG. 1 are identical;

FIG. 3 is an enlarged top plan view of the brush of FIG. 1; FIG. 4 is an enlarged bottom plan view of the brush of FIG. 1;

FIG. 5 is perspective view of a brush with a second tapered handle;

FIG. 6 is a front elevation view of the brush of FIG. 5, where the back elevation view is a mirror image of the front elevation view;

FIG. 7 is a side elevation view of the apparatus brush of FIG. 5, where the left side elevation view is a mirror image of the right side elevation view;

FIG. 8 is an enlarged cross-sectional view of the brush of FIG. 5, taken at line 8-8 in FIG. 6;

FIG. 9 is an enlarged cross-sectional view of the brush of FIG. 5, taken at line 9-9 in FIG. 6;

FIG. 10 is an enlarged top plan view of the brush of FIG. 5; FIG. 11 is an enlarged bottom plan view of the brush of FIG. 5;

FIG. 12 is a perspective view of a brush with a third tapered handle;

FIG. 13 is a side elevation view of the brush of FIG. 12, where the brush and brush handle are symmetrical about a longitudinal axis thereof such that a left side elevation view, a right side elevation view, a front elevation view, and a back elevation view of the brush of FIG. 12 are identical;

FIG. 14 is an enlarged cross-sectional view of the brush of FIG. 12, taken at line 14-14 in FIG. 13;

FIG. 15 is an enlarged cross-sectional view of the brush of FIG. 12, taken at line 15-15 in FIG. 13;

FIG. 16 is an enlarged top plan view of the brush of FIG. 12;

FIG. 17 is an enlarged front elevation view of the brush of FIG. 18;

FIG. 18 is a perspective view of a brush with a fourth tapered handle;

FIG. 19 is a front elevation view of the brush of FIG. 18;

FIG. 20 is a back elevation view of the brush of FIG. 18;

FIG. 21 is a left side elevation view of the brush of FIG. 18; FIG. 22 is a right side elevation view of the brush of FIG. 18;

FIG. 23 is an enlarged cross-sectional view of the brush of FIG. 18, taken along line 23-23 in FIG. 19;

FIG. 24 is an enlarged cross-sectional view of the brush of FIG. 18, taken along line 24-24 in FIG. 19;

FIG. 25 is an enlarged top plan view of the brush of FIG. 18; and,

FIG. 26 is an enlarged bottom plan view of the brush of FIG. 18.
